UNITED STATES PATENT OFFICE.

HUGO F. RIPKEN, OF MINNEAPOLIS, MINNESOTA, ASSIGNOR OF ONE-HALF TO CHARLES A. McCULLOCH, OF MINNEAPOLIS, MINNESOTA.

DRIFTING AND RELIEF VALVE.

1,272,718.

Specification of Letters Patent. Patented July 16, 1918.

Application filed July 10, 1918. Serial No. 108,328.

To all whom it may concern:

Be it known that I, HUGO F. RIPKEN, a citizen of the United States, residing at Minneapolis, in the county of Hennepin and 5 State of Minnesota, have invented certain new and useful Improvements in Drifting and Relief Valves, of which the following is a specification.

My invention relates to improvements in 10 drifting and relief valves for reciprocating steam engines, and especially for those employed in railway locomotives.

It will be understood that when in the 15 ordinary operation of the engine the supply of steam to the cylinder and steam chest is cut off by the closing of the throttle valve, the engine will drift for some time before it actually comes to rest. In thus drifting the piston will continue to 20 move back and forth and as no live steam enters behind the piston a partial vacuum will be formed at that point. This will cause an inrush of cold air into the cylinder through the cylinder cocks, and also 25 as soon as the valve piston in the steam chest has uncovered the cylinder port to the exhaust on that side, an inrush of smoke, cinders, and gases of combustion from the smoke box through the exhaust nozzle. 30 This is objectionable because the cold air cools the cylinder walls and steam chest and causes condensation of the steam, and the smoke, cinders, and gases of combustion are destructive of the lubrication of the cylinder. 35

It is the object of this invention to overcome these objections by providing an improved drifting or relief valve that will automatically and instantly operate to admit 40 a sufficient amount of boiler steam to the valves and cylinder while the engine is drifting even at very low speed and with the main throttle valve closed to prevent this partial vacuum being formed in the cylinder, and which will also automatically close 45 and shut off the steam when the engine comes to rest, so that there will be no escape or waste of steam through the drifting valve when the steam is not needed to prevent a 50 partial vacuum forming in drifting.

With these objects in view I have constructed a valve wherein the cylinder compression or back pressure upon the piston, a positive force existing only while the engine is in motion, is utilized to furnish the

motive power for operating the valve to open it, and steam entering from the boiler to furnish the power to close it after the back pressure has ceased owing to the stoppage of the engine and wherein the valve is 60 a ported piston valve, so that no boiler pressure will be exerted upon it in opposition to the pressure from the cylinder until the piston has been moved far enough to uncover the live steam port, so that the valve 65 will be opened whenever the cylinder pressure is sufficient to overcome the weight or inertia of the piston itself, as will always be the case when the engine is drifting, even when it is at the slowest speed and with the 70 longest cut-off obtainable in locomotive service. More particularly the invention consists in the construction, combination, and arrangement of parts hereinafter described and claimed. 75

In the accompanying drawings showing an embodiment of the invention,

Figure 1 is a vertical longitudinal section through the middle of the cylinder and steam chest of a reciprocating engine with 80 my improved valve in elevation, and

Fig. 2 is a vertical section through the middle of the valve alone.

In the drawings A represents the cylinder of a reciprocating engine, B the piston 85 working therein, and C the steam chest in which works a valve piston D, all of usual type.

The drifting valve which is the subject of this invention comprises a cylindrical casing 90 or cage 2, shown in elevation in Fig. 1 and in vertical section in Fig. 2, the interior of which is open to communication with one end of the interior of the cylinder through the medium of a pipe 3 which leads from the bottom of the valve casing into a duct 4 extending around the bushing at one end of the steam chest to the cylinder port 5 on that side of the piston B. The compressed air or steam in that end of the cylinder can thus pass through the duct 4 and pipe 3 into the valve casing below the valve. Another pipe 6 leads from the top of the valve casing and has communication with the steam chamber 7 of the steam chest. 100

Working within the valve casing 2 is a sliding valve piston 8 closed at the bottom and having an upwardly projecting sleeve extension 17. The upper portion of the valve piston is somewhat larger in diameter than 110

the lower portion and is formed with a shoulder 9 which seats against a coöperating shoulder 10 on the inside of the casing when the valve is not in operation. Just beneath 5 the shoulder 9 the sleeve extension of the valve piston is formed with a circumferential port 11 in position to communicate with a circumferential port 12 in the casing when the valve piston is moved up. The port 12 10 is in communication with a live steam inlet conduit or pipe 13 which leads from the boiler (not shown) or other source of steam supply. The ports 11 and 12 are guarded from the accidental passage of steam into 15 the cage by means of packing rings 14.

In order to prevent the hammering of the valve piston 8 in the casing and also to reduce the bottom area of the piston sufficiently to allow the steam pressure from the 20 steam chest entering above it to keep the valve piston on its seat while the main throttle valve is open and the engine is working, the valve is provided with a centrally depending plunger 15 of much less diameter 25 than the diameter of the piston and this plunger works within a dash pot 16 carried by the cage 2 a suitable distance below the valve seat 10. The plunger is shown formed with circumferential grooves to catch drippings 30 of oil and condensed steam for lubrication purposes, but this is no part of my invention.

The operation of the valve is as follows: When the pressure in the steam chamber of 35 the steam chest falls owing to the closing of the throttle valve, the compression in the forward end of the cylinder, resulting from the continued movement of the piston after the valve in the steam chest has closed the 40 cylinder port to the exhaust outlet, will force the steam in the cylinder out through the ducts 4 and 3 into the lower part of the valve cage 2 below the valve piston 8. This will throw the valve piston up and bring 45 the circumferential valve port 11 in the sleeve 17 into communication with the port 12, so that the live steam in the pipe 13 will pass into the sleeve chamber on the upper side of the valve piston 8. From this chamber 50 it will pass through the pipe 6 to the steam chest and thence through the usual channels into the cylinder thereby preventing the formation of a partial vacuum in the cylinder when the steam supply is cut off by 55 the closing of the throttle valve. The valve piston will remain in this position with the ports open to allow the steam from the pipe 13 to enter the steam chest and cylinder, until the engine comes to rest and the piston 60 no longer causes cylinder compression in the pipe 3 of valve casing 2. When the cylinder compression thus ceases the pressure of steam in the sleeve chamber of the valve piston will force the valve piston down upon 65 its seat, thereby closing the port 12 and shut-

ting off the supply of live steam from the pipe 13. After this has occurred the weight of the valve is sufficient in itself to hold the valve piston upon its seat and the valve closed.

Thus I have provided a valve which will be extremely sensitive to cylinder compression, because the upward travel of the piston will not be opposed by the counter-pressure of live steam from the boiler until the 70 lateral ports in the piston sleeve and steam conduit have come into registration so as to allow the live steam to enter the valve casing. And when the live steam inlet port is constructed so as completely to encircle the 75 piston sleeve as here shown, the pressure of the live steam against the sleeve will be exerted equally upon all sides thereof, so as to hold it in balance without crowding it against the casing, thereby avoiding friction with the casing wall.

While I prefer to use the particular valve structure shown in the drawings it will be understood that I do not limit myself to this particular form but mean to include all 80 modifications thereof which come within the principle of the invention as defined in the claims. It will also be understood that the duct 3 from the valve casing may be connected with the cylinder directly or indirectly in any convenient way, the only essential being that it be constructed and connected so as to serve as a means of communication between the cylinder and the "drifting" valve when the cylinder port to exhaust 85 is closed.

It is to be understood that such changes and rearrangements of parts may be resorted to as fall within the scope of the appended claims.

I claim as my invention:

1. In a reciprocating engine, the combination with the cylinder and steam chest, of a drifting valve comprising a valve casing open to communication with the cylinder at 110 one end and the steam chest at the other end and having intermediately a lateral inlet port for live steam, and a pressure actuated valve piston having a projecting extension normally closing said live steam inlet port 115 but adapted, when the piston is moved by the pressure in the cylinder after the main supply of steam thereto has been shut off and the engine is drifting, to slide over and uncover said live steam inlet, said valve having 120 means of communication between the casing inlet and the steam chest when said inlet port is uncovered, whereby to allow live steam to enter the valve casing beyond the piston and pass to the steam chest for the 125 purpose set forth.

2. In a reciprocating engine, the combination with the cylinder and steam chest, of a balanced drifting valve comprising a valve casing open to communication with the 130

cylinder at one end and the steam chest at the other end and having intermediately a circumferential inlet port for live steam, and a valve piston having a projecting sleeve extension normally covering said inlet port so as to prevent the live steam from entering the valve casing, said sleeve extension being formed with a circumferential port, which port, when the piston is moved by the pressure in the cylinder after the main supply of steam thereto has been shut off and the

engine is drifting, will come into registration with the live steam inlet port in the casing and allow live steam to enter the portion of the valve casing beyond the piston and pass into the steam chest.

In testimony whereof I affix my signature in presence of two witnesses.

HUGO F. RIPKEN.
